UNITED STATES PATENT OFFICE

JAY ERGENBRIGHT, OF ORIENT, IOWA

SHOCK-ABSORBING RUNNING GEAR FOR BINDERS

Application filed February 13, 1928. Serial No. 254,132.

This invention relates to improvements in the running gear of grain binders.

Heretofore the bull wheels of grain binders have been mounted in inverted U-shaped hangers which are rigidly secured to the main frames of the binders, but I have found that, during the travel of the binder over the ground surface, which is usually dry, hard, and rough at the time grain is cut and bound, the binder is subjected to a jarring motion which frequently results in inaccurate tying of the bundles of grain and a shaking of the grain and dislodgment thereof from the binder mechanism, and therefore the present invention has as its primary object to provide means for absorbing the shocks incident to travel of the binder over the surface of the ground, so that such dislodgment and loss of the grain will be avoided and tying of the bundles of grain will be effected in a more perfect manner than under the conditions above described.

Another object of the invention is to provide novel means for so mounting the hangers for the bull wheels of binders that the frame of the binder will be so cushioned as not to be subjected to the usual jarring and thus overcome the disadvantages referred to above.

While the accompanying drawings and the description which is to follow, constitute a disclosure of the preferred embodiment of the invention, it will be understood that various changes may be made within the scope of what is claimed.

In the accompanying drawings:

Figure 1 is a view in side elevation of the shock-absorbing means embodying the invention installed in connection with the main and upper frames, the bull wheel and hanger of a binder;

Figure 2 is a horizontal sectional view taken substantially on the line 2-2 of Figure 1 looking in the direction indicated by the arrows;

Figure 3 is a vertical transverse sectional view taken substantially on the line 3-3 of Figure 1 looking in the direction indicated by the arrows;

Figure 4 is a vertical front to rear sectional

view taken on the line 4-4 of Figure 3 looking in the direction indicated by the arrows;

Figure 5 is a vertical front to rear sectional view taken substantially on the line 5-5 of Figure 3 looking in the direction indicated by the arrows.

In the drawings the numerals 1 and 2 indicate in general the lower and upper frame sections of the binder, the bull wheel being indicated by the numeral 3 and the axle or spindle thereof by the numeral 4. The numeral 5 indicates the usual hanger which is of inverted U-shape as shown in Figure 3 and which is disposed to straddle the bull wheel and is provided with the usual downwardly extending yokes 6 which are provided with the usual arcuate slots 7 and the usual arcuate racks 8 at the forward sides of the slots which are in mesh with the usual pinions 9 on the spindle 4 of the bull wheel 3. The numeral 10 indicates the usual worm pinion which is fixed upon the supporting spindle 4 for the bull wheel 3, and the usual bearing frame 11 is assembled with the spindle and supports the usual adjusting shaft 12 which is provided at its lower end with the worm 13 which meshes with the said worm pinion 10, the usual handle 14 being provided at the upper end of the shaft 12 whereby the shaft may be rotated so as to rotate the pinion 10 and effect rotation of the spindle 4 and the pinions 9 thereon and thus provide for up and down adjustment of the yoke 5 and corresponding adjustment of the frame comprising the sections 1 and 2, with respect to the bull wheel 3. Heretofore, it has been the practice to connect the hangers 5 rigidly to the frame 1, but, in accordance with the present invention, such connection is dispensed with and a connecting means such as illus-

trated in the drawings is employed in lieu thereof in order to obtain the advantages and overcome the disadvantages outlined above.

In the drawings the numeral 14 indicates the usual semi-elliptic springs which are connected by shackles 15, at their ends, with the ends of the side members of the lower frame section 1, and the intermediate portions of these springs have the usual clip plates 16 assembled therewith and clamped

in place by the usual clips 17, the lower ends of the side members of the hanger 5 being bolted, in the usual manner, as at 18, to the opposite sides of the lower clip plates 16. In accordance with the invention, a pair of upright stems 19 is provided upon the upper clip plate 16 of each spring 14, and these stems are vertically slidably fitted through openings provided in bearing members 20 which are secured to the inner sides of the side members of the frame 1 in front and in rear of the respective side members of the hanger 5. Pins 21 are fitted diametrically through the stems 19 and are adapted to engage the upper sides of flanges 22 which project laterally outwardly from the side members of the hanger 5, and compression springs 23 are arranged upon the stems and bear at their lower ends against the upper clip plate 16 and at their upper ends against the bearing brackets 20.

From the foregoing description of the invention it will be understood that as the bull wheel 3 passes over inequalities in the ground surface, in the travel of the binder, any shocks of impact of the bull wheel with the inequalities in the ground surface are absorbed due to the provision of the springs 23 and the arrangement of these springs in the manner illustrated and described, it being evident that, in the instance of the present invention, a yieldable connection is provided between the hanger 5 and the frame 1 instead of the fixed connection which is ordinarily provided between these parts.

Having thus described the invention, what I claim is:

1. In a binder, the combination with the binder frame, the bull wheel, and the hanger in which the bull wheel is adjustably mounted, of a cushioning spring suspended at its ends from the frame, means connecting the hanger with the intermediate portion of the spring, bearings upon the frame and other bearings upon the hanger, rods connected to the intermediate portion of the spring and fitting slidably in the said bearings, means positively limiting the downward sliding movement of the rods through the bearings upon the hanger, and compression springs arranged upon the rods between the intermediate portion of the first mentioned spring and the bearings upon the said frame.

2. In a binder, the combination with the binder frame, the bull wheel, and the hanger in which the bull wheel is adjustably mounted, of a spring assemblage suspended at its ends from the frame, means securing the hanger to the intermediate portion of the spring assemblage, compression springs interposed between the frame and the intermediate portion of the spring assemblage, and means connected with the spring assemblage and coacting with abutment portions upon

the hanger for limiting the displacement of the frame with respect to the hanger.

In testimony whereof I affix my signature.

JAY ERGENBRIGHT.
